ROTARY VALVE

Lauritz Emil Mylting, Merchantville, N. J., assignor to The Allen-Sherman-Hoff Company, Philadelphia, Pa., a corporation of Pennsylvania

Application January 29, 1948, Serial No. 4,970

3 Claims. (Cl. 222—368)

1

The present invention relates generally to the material handling art and is more particularly concerned with a new rotary valve for transferring or moving finely divided dry solids, such as fine ashes, from a hopper or the like.

Rotary valves which have been used heretofore for removing finely divided solids from hoppers have comprised a thin plate depending from the hopper and surrounding the hopper discharge opening and a rotor which initially engaged the lower edge of the plate. When the solids were abrasive in character, the peripheral surfaces of the valve or the opposed sealing surfaces of the plate, or both of these surfaces, were abraded and worn away. As a result of such wear, fine solids could leak out of the hopper when the valve was not rotating and the amount of leakage increased as the wear increased. When the wear became as great as could be tolerated, the valve was replaced. The rate of wear of these parts increased considerably when the valve was used to transfer solids from a chamber under a given pressure to another chamber where another pressure existed, for example, from a hopper whose interior was maintained at subatmospheric pressure to a chamber where atmospheric pressure prevailed. Also, the extent of leakage of solids and gases past the valve increased with the increase in gas pressure differential, and furnace efficiency was often impaired when wear admitted air to enter a hopper and raise the subatmospheric pressure preferred therein. Although these shortcomings of rotary valves have long been known, no one, so far as I know, has proposed a rotary valve which would be free from these disadvantages.

The present invention provides rotary valves which can be used several times as long as prior valves and even under differential gas pressures without leakage of solids or gases past the valve, which includes new sealing means and in which the sealing means may be replaced quickly, readily and inexpensively when worn beyond a predetermined extent.

The fundamental differences between the means of my present invention and previous devices and the reasons for the superiority of devices embodying my invention over those of the art will become apparent upon consideration of the following detailed description and the drawings accompanying and forming a part of this specification, in which

Figure 1 is a vertical sectional view of a rotary valve embodying this invention taken axially of the rotor;

2 Figure 2 is a view taken on line 2—2 of Fig. 1; Figure 3 is a vertical sectional view of another rotary valve embodying this invention, taken axially of the rotor; and

5 Figure 4 is a view taken on line 4—4 of Figure 3.

Viewed generally, the device of my present invention comprises a cylindrical, compartmented, rotary valve, preferably disposed within a housing, means for rotating the valve, and means for sealing the valve at all times comprising a flanged shoe. The rotor and sealing means therefor, in accordance with this invention, are adjustable relative to each other so that as the parts wear in use they may be re-adjusted to maintain the desired sealing action and replaced when worn beyond the range of adjustment.

The device of Figs. 1 and 2 comprises a valve housing, a rotary valve and a valve seal. The 10 valve housing 1 is preferably fabricated and has openings through its upper and lower ends surrounded by bolt flanges 2 and 3, respectively. A gasket retaining plate 4, having a central opening, is positioned on top of flange 2. Bolts (not shown) extend through flange 2 and plate 4 to secure the housing to a hopper (not shown) having a bottom discharge opening aligned with the opening through plate 4. The housing 1 has a bracket structure extending from one side thereof, including braces 5 and a bearing housing 6.

15 A shaft 10 is rotatably mounted in bearings 11 carried in bearing housing 6 and is provided at its outer end with a sprocket 12 for engagement with a drive chain (not shown) and at its end within housing 1 is integrally connected to a disc 13. Thrust collars 14 and 15 are fastened to shaft 10 at either end of bearing housing 6. Packing 16 is retained in place about shaft 10 within an outwardly extending annular flange 17 by ring 18 which is threaded into the flange. The disc 13 is provided on its inner face with an axially extending flange 20 and with a threaded hole 21 located on the axis of the disc. The disc 13 and shaft 10 serve to support and rotate the 20 rotor of the valve.

The valve rotor 25 is substantially cylindrical and comprises a hub 26, end discs 27 and 28 integral therewith and a plurality of radial walls 29 integral with the hub and with discs 27 and 50 28 and terminating in arcuate flanges 30 which have outer surfaces which are segments of a cylinder. The peripheral surfaces of the discs and the outer surfaces of flanges 30 comprise parts of a cylinder surface. The radial walls 29, hub 26 and end discs 27 and 28 form compart-

ments 31 which are open at their radial outer ends to receive solids flowing from the hopper through the hole in upper plate 4. End disc 28 of rotor 25 has an outwardly projecting annular rib 32 which is located by flange 20 and seats on disc 13. The hub 26 of the rotor 25 has an axial hole extending therethrough. A threaded rod 32 extends through that hole and is threaded into the axial hole 21 in disc 13. Nut 33, threaded on the outer end of rod 32 and pressing against rotor 25, serves to secure the rotor to disc 13 for rotation therewith.

The valve seal comprises a collapsible, tubular resilient ring 35 and a shoe 36. The shoe comprises a cylindrical portion 37 which is slidable in the opening defined by flange 2 of the housing and a rotor engaging portion 38, which is generally rectangular in plan view, is substantially as long as rotor 25 and is not more than about 120° in width measured along the under surface which is engageable with the rotor. The shoe 36 is positioned in housing 1 by bolts 40 which extend up through the housing and nuts 41 which engage the bolts outside of the housing and beneath flange 2. The resilient ring 35 lies between the upper end of portion 37 of the seal and plate 4 and may be compressed more or less by adjusting the nuts 41 on bolts 40.

It will be noted that shoe 36 prevents flow of gases or solids past rotor 25 and into or out of the hopper. The end portions 45 of the shoe overlie discs 27 and 28 while the side portions 46 are long enough circumferentially to more than bridge the gap between any adjacent pair of flanges 30 on partition walls 29.

When the parts of the device of Fig. 1 are in assembled position, the lower curved surfaces of parts 45 and 46 of shoe 36 are substantially in engagement with the cylindrical surfaces of discs 27 and 28 and flanges 30 of rotor 25 and resilient ring 35 engages the under side of plate 4 and the upper end of shoe 36 and constitutes the packing between these two members within flange 2 of the housing 1. Any abrasive wear of either the cylindrical surface of rotor 25 or the under surface of shoe 36 may be compensated for by a lowering shoe 36 until substantial engagement of the shoe and rotor occurs. This lowering action may be accomplished by turning nuts 41 on studs 40. Resilient ring 35 serves not only to seal against the escape of flow of air or gas between the housing, plate and shoe, but also to urge the shoe downwardly against rotor 25. Obviously ring 35 may be replaced by other means such as a bellows type seal or by springs or other resilient means when the shoe 36 has a sufficiently close sliding fit in the opening through the top of housing 1 to seal satisfactorily.

It will be noted that shoe 36 does not engage over more than 120° of the circumferential extent of rotor 25. Two main objects are attained by observing this maximum dimension. The grinding of the lower surface of the shoe is facilitated since three shoes, each 120° long, may be chuck and ground at one time. Also, adjustments may be made for wear until the shoe is substantially worn out because the surfaces of the shoe and rotor continue to conform to each other as the wear progresses.

The device shown in Figs. 3 and 4 is quite like the device of Figs. 1 and 2. Rotor 60 is quite like rotor 25 but has a smaller number of radial walls 61 and has correspondingly longer arcuate flanges 62 at the outer ends of those walls. Instead of being carried in the overhung position

5 of rotor 25, rotor 60 is mounted on shaft 63 which extends through the axial opening in hub 64 of the rotor and is mounted in bearings 65 carried by brackets 66 on the ends of housing 67 which corresponds to housing 1 of Figs. 1 and 2. Sprocket wheel 68 on shaft 63 is provided for engagement with a drive chain and serves to rotate the shaft and rotor. The shoe 70 is quite like shoe 36 and is similarly and adjustably mounted in the housing. Upper plate 71 corresponds to plate 4 of Fig. 1, while the resilient ring 72 corresponds to ring 35 of Fig. 1.

It will be noted that the lower surfaces of opposed side portions 73 of shoe 70 are sufficiently long circumferentially to bridge the space between two adjacent flanges 62 so that at no time is one of the compartments of the rotor in communication with both the interior and exterior of the hopper.

20 It will be obvious that various changes in construction may be made in the devices illustrated and described herein. All such changes, which do not amount to invention, are intended to come within the present invention and are comprehended within the scope of the present claims.

Having thus described the invention so that others skilled in the art may be able to understand and practice the same, I state that what I desire to secure by Letters Patent is defined in what is claimed.

I claim:

1. A device for feeding fine solids comprising a substantially cylindrical rotor including a hub, end discs spaced axially apart on the hub and a plurality of radial walls connected to the discs, extending outwardly from the hub to the outer periphery of the discs and defining with said discs a plurality of separate compartments open at their outer ends, a sealing shoe having opposed side portions each having under surfaces longer circumferentially of the rotor than the space between adjacent radial walls, and means including a plurality of shoe-supporting studs fastened to, and extending from, the shoe for adjustably positioning said shoe vertically relative to said rotor.

2. A device for feeding fine solids comprising a substantially cylindrical rotor including a hub, end discs spaced axially apart on the hub and a plurality of radial walls connected to the discs, extending outwardly from the hub to the outer periphery of the discs and defining with said discs a plurality of separate compartments open at their outer ends, a sealing shoe having opposed side portions each having under surfaces longer circumferentially of the rotor than the space between adjacent radial walls, means including a plurality of shoe-supporting studs fastened to, and extending from, the shoe for adjustably positioning said shoe vertically relative to said rotor, and means comprising a collapsible, tubular, rubber ring engaging said shoe and urging it toward said rotor.

3. A device for feeding fine solids comprising a substantially cylindrical rotor including a hub, end discs spaced axially apart on the hub and a plurality of radial walls connected to the discs and extending outwardly from the hub to the outer periphery of the discs and defining with said discs a plurality of separate compartments open at their outer ends, a sealing shoe having opposed side portions each having under surfaces longer circumferentially of the rotor than the space between adjacent radial walls, a housing enclosing said rotor and shoe, and having

openings in its upper and lower portions for admission and discharge of fine solids, means including a plurality of studs fastened to the shoe and extending upwardly therefrom through apertures in the upper portion of said housing for adjustably positioning said shoe vertically relative to said rotor, and means comprising a collapsible, tubular, rubber ring engaging said shoe and urging it toward said rotor.
